UNITED STATES PATENT OFFICE.

SYLVENDER F. MAYNARD AND HOMER N. PARKER, OF LEOMINSTER,
MASS., ASSIGNORS TO WILLIAM S. REED, OF SAME PLACE.

TOY.

SPECIFICATION forming part of Letters Patent No. 231,435, dated August 24, 1880.

Application filed May 26, 1880. (No model.)

To all whom it may concern:

Be it known that we, SYLVENDER F. MAYNARD and HOMER N. PARKER, both of Leominster, in the county of Worcester and State of Massachusetts, have invented an Improved Fastening for Toys, of which the following is a full, clear, and exact description, reference being had to the accompanying drawings, making part of this specification, in which—

10 Figure 1 is an elevation of two upright toy figures connected by a rod or wire, the limbs of each figure being united to its body by means of our improved fastenings. Fig. 2 represents a figure having a device applied to one 15 of its eyelet-connections in order to whirl the figure thereon. Fig. 3 is a longitudinal section through one of the eyelets we employ.

Our present invention consists in the method 20 of connecting the various limbs, members, or moving portions of toy figures or blocks by means of eyelets, the parts being so united as to insure sufficient friction for retaining them in any desired position after adjustment, the 25 openings in the eyelets serving as ready means by which separate figures or separate portions of the same figure may be united by a wire, rod, or string, so as to render them capable of acting in unison.

Our invention also consists in the combination, 30 with a toy figure or block having its portions united by eyelets, of a device having a handle provided with a rod or wire, the said device being designed for whirling the figure thereon.

35 To enable others skilled in the art to understand and use our invention, we will proceed to describe the manner in which we have carried it out.

In the said drawings, A represents the body 40 or trunk of a toy figure of a gymnast or clown, to which are secured, by means of eyelets a a, the two legs b b and two arms, c c, one eyelet passing through both arms and the body and another eyelet passing through both legs 45 and the body, the jointed connections thus formed having just sufficient friction to enable the limbs to remain in any desired position

after adjustment. By the use of the eyelet a wire, rod, or string can be attached to the figure with great facility, thus affording a ready 50 connection with a horizontal bar or trapeze, or for uniting two figures, which, when loosely connected by a wire passing through their eyelets, may be moved independently of each other or of the connection between them, said 55 figures acting simultaneously when joined by a rigid connection formed by a rod having its ends pressed into the eyelet-openings with sufficient friction to hold them together.

The position of the toy when its limbs are 60 united to the body by eyelets, is susceptible of an endless amount of changes. The eyelet-connection is cheaply applied, secure, and durable, and has a finished appearance, and a wire or string, d, provided with a handle, B, 65 Fig. 2, is adapted to be passed through it to enable the toy to be swung around, thus affording a novel source of amusement.

In the drawings accompanying this application the figures are represented with their 70 limbs or portions provided with hook-shaped projections. But this feature is not our invention; consequently we lay no claim thereto.

Furthermore, we are aware that Patent No. 172,709, dated January 25, 1876, describes and 75 claims the limbs of toy figures joined or connected by solid rivets and interposed friction-washers, to which construction we therefore lay no claim.

We claim—

1. The limbs and other parts of a toy figure united by eyelets, substantially as and for the purpose described.

2. The combination, with a toy figure united by eyelets, of a rod, d, having a handle, B, on 85 which the figure is adapted to be whirled, as and for the purpose described.

Witness our hands this 22d day of May, 1880.

SYLVENDER F. MAYNARD.
HOMER N. PARKER.

In presence of—

JAMES BENNETT,
W.M. S. REED.
